LAMINATING PRESS FOR IDENTIFICATION CARDS OR THE LIKE

Robert W. Carver, Chatham, N. J.

Application September 20, 1957, Serial No. 47,802

Term of patent 7 years

(Cl. D63—1)

Fig. 1.

Fig. 2.

Fig. 3.

Fig. 1 is a perspective view of a laminating press for identification cards or the like, embodying my new design, showing the front and one side thereof;

Fig. 2 is an enlarged front elevational view thereof; and

Fig. 3 is an enlarged side elevational view of the press opposite to that shown in Fig. 1.

The rear of the press is substantially plain.

I claim:

The ornamental design for a laminating press for identification cards or the like, as shown and described.
